CLAIM

We claim the ornamental design for a television with rollable display, as shown and described.

DESCRIPTION

FIG. 1 is a perspective view of a television with rollable display showing the new design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof;

FIG. 7 is a bottom plan view thereof;

FIG. 8 is a perspective view of the television with rollable display of FIG. 1 shown in an alternate state with the display partially rolled up;

FIG. 9 is a front elevation view thereof;

FIG. 10 is a rear elevation view thereof;

FIG. 11 is a left-side elevation view thereof;

FIG. 12 is a right-side elevation view thereof;

FIG. 13 is a top plan view thereof;

FIG. 14 is a bottom plan view thereof;

FIG. 15 is a perspective view of the television with rollable display of FIG. 1 shown in an alternate state with the display fully rolled up;

FIG. 16 is a front elevation view thereof;

FIG. 17 is a rear elevation view thereof;

FIG. 18 is a left-side elevation view thereof;

FIG. 19 is a right-side elevation view thereof;

FIG. 20 is a top plan view thereof; and,

FIG. 21 is a bottom plan view thereof.

(Continued)

The broken lines illustrates portions of the television with rollable display that form no part of the claimed design.
